US00D762675S

(12) **United States Design Patent**
Lim et al.

(10) **Patent No.:** US D762,675 S
(45) **Date of Patent:** ** Aug. 2, 2016

(54) **DISPLAY SCREEN OR PORTION THEREOF
WITH GRAPHICAL USER INTERFACE**

(71) Applicant: **Samsung Electronics Co., Ltd.**, Suwon-si (KR)

(72) Inventors: **Eun-Sil Lim**, Seoul (KR); **Jee-Yeun Wang**, Seoul (KR); **Wan-Soo Lim**, Seongnam-si (KR)

(73) Assignee: **Samsung Electronics Co., Ltd.**, Suwon-si (KR)

(**) Term: **14 Years**

(21) Appl. No.: **29/457,474**

(22) Filed: **Jun. 10, 2013**

(30) **Foreign Application Priority Data**

Feb. 23, 2013 (KR) 30-2013-0009602

(51) **LOC (10) Cl.** **14-04**

(52) **U.S. Cl.**

USPC **D14/486**

(58) **Field of Classification Search**

USPC D14/485-495

(57) **CLAIM**

The ornamental design for a display screen or portion thereof with graphical user interface, as shown and described.

DESCRIPTION

The sole FIGURE is a front view of a display screen or portion thereof with graphical user interface, showing our new design.

The broken line showing of the display screen and elements of a graphical user interface are included for the purpose of illustrating portions of the article and form no part of the claimed design.

1 Claim, 1 Drawing Sheet
